WILLIAM T. GEISSINGER.
INVENTOR.

BY *William A. Kirtle*

ATTORNEY.

UNITED STATES PATENT OFFICE.

WILLIAM T. GEISSINGER, OF PITTSBURGH, PENNSYLVANIA.

DESIGN FOR A FONT OF PRINTING-TYPE.

50,191.

Specification for Design.

Patented Jan. 16, 1917.

Application filed August 14, 1916. Serial No. 114,935. Term of patent 14 years.

To all whom it may concern:

Be it known that I, WILLIAM T. GEISSINGER, a citizen of the United States of America, residing at Pittsburgh, in the county of Allegheny and State of Pennsylvania, have invented a new, original, and ornamental Design for a Font of Printing-Type, of which the following is a specification, reference being had to the accompanying drawing, forming part thereof.

Having set forth my invention, what I claim as new is:—

The design for a font of printing type as shown.

In testimony whereof, I affix my signature in the presence of two witnesses.

WILLIAM T. GEISSINGER.

Witnesses:

JOHN F. SWEENEY,
RAYMOND J. GRAB.

Copies of this patent may be obtained for five cents each, by addressing the "Commissioner of Patents, Washington, D. C."
